Claims priority, application Germany October 16, 1950

7 Claims. (Cl. 123—193)

1

The present invention relates to cylinder heads and, more particularly, concerns a cylinder head for air cooled internal combustion engines, which is connected to the cylinder pertaining thereto by means of screws or bolts and is provided with channel means adapted to communicate with said cylinder to convey gaseous media thereto and/or therefrom.

One of the most difficult problems in the designing of air cooled internal combustion engines, especially of an air cooled diesel engine with a combustion chamber separate from the main combustion chamber, consists in the designing of the cylinder head. This fact has its reason in the almost unsurmountable problem of properly transferring to the cooling air the heat conveyed to the cylinder head by the combustion process. In this connection, the most endangered part of the cylinder head is the wall or web between the valves. In order sufficiently to cool said web, it is necessary to blow a sufficiently large quantity of cooling air from outside the cylinder head above said web. However, the cross section available for the flow or passage of cooling air for this purpose are excessively narrowed down by the passages or channels leading outwardly from said valves. Consequently, prior to the present invention, the cooling of the web area of the cylinder head was always insufficient. Thus, as a result of overheating of the web, cracks in the cylinder head occurred and were unavoidable.

It is, therefore, an object of this invention to provide an air cooled cylinder head for internal combustion engines which will overcome the above mentioned drawbacks.

It is another object of this invention to provide an air cooled cylinder head for internal combustion engines, in which the cross section of the passage through which the cooling air may reach the web area between the valves will be materially increased.

It is still another object of this invention to provide an air cooled cylinder head for internal combustion engines, in which the connecting screws or bolts for connecting the cylinder head to the cylinder pertaining thereto will not force the passages, controlled by the valves and intended for conveying gaseous media therethrough, to be located closer relative to each other.

It is also an object of this invention to provide an air cooled cylinder for internal combustion engines, in which the valves controlling the gas conveying channels or passages are so arranged in the cylinder head as to yield an increased free area therebetween through which an increased quantity of air may reach the web area between said valves.

2

These and other objects and advantages of the invention will appear more clearly from the following specification in connection with the accompanying drawings, in which:

5 Fig. 1 illustrates a top view, partly in section, of one embodiment of a cylinder head according to the present invention.

Fig. 2 represents a section along the line II—II of Fig. 1.

Fig. 3 is a section along the line III—III of Fig. 1.

10 Fig. 4 is a section similar to that of Fig. 3 but illustrates a slight modification thereover concerning the connection of the cylinder head to the cylinder.

General arrangement

15 In order to increase the space between the valves and thus to enlarge the passage through which the cooling air may carry away the heat of the web, according to the present invention, the connecting screws or bolts for connecting the cylinder head to the cylinder pertaining thereto and the channels or passages for conveying the gaseous media are so arranged that the central axes of the connecting screws or bolts and the channels or passages for conveying the gaseous media intersect.

20 According to the invention, the connecting screws or bolts and the channels or passages for conveying the gaseous media are, so to speak, located at one and the same place. Consequently, considerably less space than heretofore necessary is required for the connecting screws or bolts and the said channels or passages. It is obvious that such an arrangement leaves more space for the passage of cooling air through the cylinder head and gives more freedom in the arrangement of cooling fins wherever necessary, particularly at the web area between the valves.

Structural arrangement

25 Referring now to the drawings in detail, the structure shown therein represents a cylinder head 1a for an air cooled four stroke cycle internal combustion engine of the injection type, which is provided with a combustion chamber 1 separate from the cylinder space of the cylinder pertaining thereto. The cylinder head is also provided with suspended valves 2, 3 of which the valve 2 represents the inlet valve, whereas the valve 3 represents the outlet valve. The channels or passages controlled by the valves 2 and 3 are designated with the reference numerals 4 and 5 respectively.

30 The cylinder head 1a is connected to the cyl-

cylinder 23 by connecting screws or bolts 6, 7, 8, and 9. These screws or bolts are passed from the cylinder head through the cylinder into the crank case (not shown in the drawing). The cylinder head is characterized in that the connecting screws or bolts 6 and 7 and the channels or passages 4 and 5 for conveying the gaseous media are arranged so that the central axes of said screws or bolts and of said channels or passages intersect. When evenly distributing the screws 6, 7, 8 and 9 over the marginal circumferential area of the cylinder, the great advantage is obtained that between the gas conveying channels or passages there will be more space for the passage of cooling air. Consequently, also more cooling fins 10 can be arranged between the channels or passages 4 and 5. The connecting screws 6 and 7 lead from the interior of the gas conveying channels 4 and 5 to the crank case. In order to prevent the screws or bolts 6 and 7 from decreasing or impeding the free passage of the gaseous media through said channels 4 and 5, recesses 11 are provided in the interior surfaces of said channels or passages 4 and 5 for receiving the heads or, if desired, the nuts of the connecting screws or bolts. In order to cover up the heads or nuts of the screws or bolts 6 and 7, caps 22 are provided which are arranged in said recesses and are retained therein in any convenient manner, e. g. by a clamp fitting. If desired, also clamping screws, accessible from the outside of the cylinder head may be used for retaining the caps 22 in the recesses 11. When the cylinder head is made of light metal, it is particularly advantageous to form the base surface of said recesses 11 by strong steel rings or washers 12 which are preferably cast into the cylinder head. In this way, the specific stress of the cylinder head caused by the forces exerted by the screws or bolts 6 and 7 is materially reduced. It is particularly advantageous to arrange the channels or passages 4 and 5, as shown with the channel 4, so that the axis of their openings toward the outside substantially registers with the longitudinal axis of the respective screw or bolt 6, 7. The screws or bolts are thus easily accessible after removal of the connecting pipes normally connected to said channels. If, however, as shown with the outlet channel or passage 5, the channel or passage has its opening toward the outside transverse to the central axis of the connecting screw or bolt, it is convenient, in order to make the screw or bolt easily accessible, to provide an aperture 14 in the channel wall facing the head or nut of the screw or bolt 6. This aperture may be closed by a threaded stopper 13 or the like.

A further improvement in the passage of cooling air between the gas conveying channels 4 and 5 may be obtained by arranging the valves 2 and 3 at an angle with regard to each other, the apex of said angle being located toward the cylinder pertaining to the cylinder head. In this way, the space between the gas conveying channels is still further increased. The cylinder head illustrated in the drawing has additional advantages due to the fact that the inlet passages 4 and the outlet passage 5 are so arranged as to be associated with two connecting screws 6 and 7 respectively, while the combustion chamber 1 is located approximately between the other two connecting screws or bolts 8 and 9. In this way, the access of air to the space between the two gas conveying channels 4 and 5 is improved. This is the case when the cooling air is blown against

the cylinder head from that side at which the combustion chamber is located, as well as when the cooling air is blown from the opposite side against the cylinder head.

In some instances it may be advantageous to pass the connecting screws through the gas conveying channels toward the outside as illustrated in Fig. 4. In such an instance, that portion of the connecting screws which extends through the said channels is preferably surrounded by a cover 25 which may be cast into the cylinder head. This cover is preferably shaped according to aerodynamic principles. It may also be mentioned that, if the occasion should call for, also more than one connecting screw may be passed through one gas conveying channel.

The arrangement according to the present invention is of advantage also in such instances in which the cylinder head together with the cylinder pertaining thereto is in a manner known per se suspended on a plate arranged above the cylinder head, said plate being tied up to the crank case. With the internal combustion engines of this type, it was always necessary heretofore, to provide additional material from the cylinder lid upwards laterally of the gas conveying channels into which material the connecting screws are screwed. The arrangement according to the present invention makes the provision of such additional material unnecessary so that the space heretofore taken up by the said additional material will become available for the gas conveying channels.

The invention is applicable not only to four stroke cycle internal combustion engines but also to two stroke cycle internal combustion engines. With the last mentioned type of engines, the difficulties described in the opening paragraphs of this specification occur to an increased extent when the cylinder head comprises two outlet valves arranged side by side. The reason for this consists in that in such an instance, the web located between the said two outlet valves is heated to a far greater extent. For such a web it is, therefore, particularly important to be cooled from the outside by cooling air.

The two valves 6 and 7 are actuated by rocker arms 15 which are arranged above the cylinder head in a cup or pan 16 integrally cast with the cylinder head. The cup or pan 16 is covered toward the outside by a protective cap 17. The push rods 18 for actuating the rocker arms 15 extend from below the cup or pan 16 into the latter through corresponding apertures. In order to provide for easy accessibility of the connecting screws or bolts 8 and 9, the bottom 19 above the screws or bolts 8 and 9 is provided with two openings respectively, which are adapted in a leak-proof manner to be closed by threaded stoppers 21 to prevent oil from leaking therethrough.

It is, of course, understood that the present invention is, by no means, limited to the particular constructions shown in the drawings but also comprises any modifications within the scope of the appended claims.

What we claim is:

1. In an air cooled cylinder head for internal combustion engines, channel means extending through said head for conveying gaseous media therethrough, passage means extending from each of said channel means to the bottom of said cylinder head for receiving and passing connecting screws therethrough to connect said cylinder head to the cylinder pertaining thereto, said

channel means and said passage means being arranged so that the respective axes thereof intersect, said channel means at the intersection with the respective passage means being provided with a recess for receiving the head or nut of the respective connecting screw, and closure means respectively mounted in said recesses for covering up said heads or nuts.

2. An air cooled cylinder head according to claim 1, in which the top surface of said closure means is substantially flush with the bottom of the adjacent channel means.

3. An air cooled cylinder head according to claim 1, which includes steel ring means respectively arranged at the bottom of said recesses and cast into said cylinder head.

4. In an air cooled cylinder head for internal combustion engines, channel means extending through said cylinder head and adapted to convey gaseous media therethrough, passage means extending from the interior of said channel means to the bottom of said cylinder head for receiving and passing screws therethrough to connect the cylinder head to the cylinder pertaining thereto, said channel means and said passage means being arranged so that at least a portion of that end of each channel means which is remote from the bottom of the cylinder head is in alignment with passage means, each of said channel means being provided with a recess at the entrance to said passage means for receiving the head or nut of said screws, and cap means inserted in said recesses for respectively closing said recesses with regard to said channel means.

5. In an air cooled cylinder head for internal combustion engines, channel means extending along a curved path from the bottom area of said cylinder head to one side thereof to convey a gaseous medium through said cylinder head, passage means extending along a straight path from the bottom area of said cylinder head upwardly so as to intersect with said channel means and adapted to allow the passage of screw means therethrough for connecting said cylinder head to a cylinder, said channel means being provided with a recess at the intersection of said channel means with said passage means to receive the head or nut of said screw means, said cylinder head being provided with additional passage means accessible from the outside of said cylinder head and substantially registering with said first mentioned passage means, closure means detachably mounted in said additional passage means to close the latter toward the outside of said cylinder head, and cap means inserted in said recess for closing the latter with regard to said channel means.

6. An air cooled cylinder head for internal combustion engines which comprises in combina-

tion, a combustion chamber spaced from the bottom of said cylinder head, an intake channel, a discharge channel, said channels being arranged to convey gaseous media therethrough, a first pair of passage means respectively intersecting with said channels and extending from the interior thereof to the bottom of said cylinder head, said first pair of passage means being adapted to receive and pass therethrough connecting screws for connecting said cylinder head to the cylinder pertaining thereto, each of said channel means being provided with a recess at the intersection with the adjacent passage means to receive the head or nut of the respective screw to be passed through the adjacent passage means, cover means respectively inserted in said recesses to close the same with regard to the adjacent channel, and a second pair of passage means outside said channels for receiving and passing therethrough additional connecting screws, said combustion chamber being located substantially between the passage means of said second pair of passage means.

7. In an air cooled cylinder head for internal combustion engines, especially diesel engines having a combustion chamber spaced from the bottom of said cylinder head, gaseous media conveying means extending through said head, said head also being provided with passage means respectively branching off from said conveying means and leading to the bottom of said head to allow the passage of connecting screws therethrough for connecting said cylinder head with the cylinder pertaining thereto, said gaseous media conveying means respectively having their walls at the branching off points of said passage means provided with recesses for receiving the head or nut of the respective connecting screw, and cover means respectively detachably retained in said recesses for completely covering up the upper portion of said heads or nuts and having their outer contour conforming to the contour of the adjacent wall portion of said conveying means to thereby protect said heads or nuts against heat while reducing to a minimum the flow resistance adjacent said recesses.
